Primary Examiner — Kevin K. Rudzinski*Assistant Examiner* — Clare Ann Gannon(74) *Attorney, Agent, or Firm* — Fross Zelnick Lehrman & Sissu, P.C.; Lawrence E. Apolzon, Esq.(57) **CLAIM**

The ornamental design for a shoe, as shown and described.

DESCRIPTION

FIG. 1 is a front perspective view of a shoe showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a front perspective view of an alternative embodiment of the shoe shown in FIG. 1;

FIG. 8 is a right side view thereof;

FIG. 9 is a left side view thereof;

FIG. 10 is a front view thereof;

FIG. 11 is a rear view thereof; and,

FIG. 12 is a top view thereof.

The broken lines depict portions of the shoe that form no part of the claimed design.

1 Claim, 12 Drawing Sheets(56)
